UNITED STATES PATENT OFFICE.

GEORGE W. LIEBERUM, OF BRIDGEPORT, CONNECTICUT, ASSIGNOR TO GENERAL ELECTRIC COMPANY, A CORPORATION OF NEW YORK.

ELECTRIC SWITCH.

Application filed February 6, 1924. Serial No. 691,040.

To all whom it may concern:

Be it known that I, GEORGE W. LIEBERUM, a citizen of the United States, residing at Bridgeport, in the county of Fairfield, State of Connecticut, have invented certain new and useful Improvements in Electric Switches, of which the following is a specification.

The present invention relates to electric switches and more especially to the double action rotary type of snap switches.

This type of switch is usually designed with one off or open circuit position of its movable pole member, and a plurality of closed circuit positions thereof so that electric current may be delivered by means of the switch to any one or several of a group of translating devices, such as heater coils or electrolier lamps, or wholly disconnected therefrom by rotary movement of the switch handle, and by reason of the double action feature thereof the pole member may be moved in either direction to the nearest desired operating position.

The object of my invention is to provide an improved double action rotary snap switch which shall be composed of few parts and of low manufacturing cost and be at the same time of sturdy construction and not liable to become inoperative through severe and extended use.

One embodiment of the invention is shown in the accompanying drawing in which Fig. 1 is a plan view of a double action snap switch with the cap and handle parts omitted; Fig. 2 is a vertical section thereof taken on line 2—2 of Fig. 1; Fig. 3 is a vertical section of the movable parts taken on line 3—3 of Fig. 1; Fig. 4 is a perspective view of the movable parts, except the shaft, shown disassembled; Fig. 5 is a perspective view of the actuating shaft and the spring, and Fig. 6 is a plan view of the stop plate, holding detent and eccentric connections between the detent and shaft.

The stationary part of the switch comprises a round base 1 of porcelain provided near its periphery with vertical passageways 2 for the current carrying wires (not shown), pairs of small holes 3 for screws 4 whereby the stationary contact posts 5 are secured to the upper surface thereof and a central aperture 6 for the reception of the quill 7, in which the shaft 8 is journalled. The upper end of the quill 7 is rigidly at-

tached to the stop plate 9 which is anchored to its seat in a recess 10 in the upper surface of the base 1 by a nut 11 threaded on the lower end of the quill 7 and pressing against a lock washer 12 in engagement with the under surface of the base.

The stop plate 9 in the present instance has four equally spaced stop lugs 13 turned upwardly at its respective corners.

The stationary contact posts 5 are provided as usual with binding screws 14 whereby the conductors are connected.

The operating shaft 8 has rigidly connected to intermediate points thereof two crank plates 15 with oppositely directed lugs 16. Between the crank plates the shaft is loosely surrounded by a bushing 17 and the latter is loosely surrounded by a helical spring 18 with its ends 19 turned radially outward to bear against the opposed crank lugs 16.

A supporting plate 20 for the pole pieces 21 and 22 is freely mounted on the shaft 8 just beneath the lower crank plate 15 and an eccentric 23 is rigidly attached to the shaft beneath the lower crank plate 15, as indicated in Figs. 2 and 3.

The eccentric 23 freely enters a central aperture in the inner end of a sliding detent 24 having its operative end of a width corresponding to the space between any two adjacent stop lugs 13 and an upturned finger 25 is provided at the center of the operative end for engagement in a radial slot 26 in the supporting plate 20 whereby the detent 24 and the movable pole member are locked against relative rotation while permitting an in and out movement of the detent under the action of its eccentric.

The shaft 8 is positioned vertically in the quill 7 by the eccentric 23 engaging the upper end of the latter while a notched ring 27 rigidly attached to the lower end of the shaft engages the lower end of the quill through a washer 28.

The supporting plate 20 of the movable pole member is provided with two upwardly extending parallel studs 29 with bearing shoulders 30 near their lower ends. The pole pieces 21 and 22 are each composed of a pair of phosphor bronze punchings 31 with three radial contact arms 32 and each pair is centrally bound between two plates of insulation 33 reinforced by metal washers 34. The pole pieces 21 and 22 have in-

terposed between them a disk 35 of insulation and a second disk 36 is positioned above the upper pole piece 22 to serve as arcing barriers. The pole pieces and the barrier disks 35 and 36 are punched with relatively large center apertures 37 to provide for the ready reception therein of the operating shaft 8 and its cranks 15 and four spaced holes 38 corresponding diagonally to the spacing of the studs 29 so that they may be assembled in desired relation thereon. A clamping plate 39 having its ends apertured to receive the ends of the studs 29 is assembled on top the upper barrier disk 36 and the studs headed over, as indicated in Fig. 3, to secure the pole pieces 21 and 22 and the supporting plate 20 together as a unit. The clamping plate 39 is provided with a folded-over arm 40 having a hole 41 formed therein to receive and bear upon the shaft 8 above the upper crank plate 15.

The upper spring end 19 normally bears against an edge of the arm 40 while the lower spring end 19 normally bears against one of the studs 29.

Referring to Figs. 1 and 5, it will be evident that when the shaft 8 is turned clockwise the upper crank 15 will cause a corresponding movement of the upper spring end 19 while the supporting plate 20 and all parts carried thereby are held against rotary movement by the detent 24 which is in engagement with a lug 13 and thus effecting a winding up or tensioning of the spring 18 until the eccentric 23 has moved with the shaft through a sufficient angle to have retracted the operative end of the detent from its engagement with the instant stop lug 13 whereupon the spring reacts to throw the movable pole member with a snap action until arrested by the detent engaging the next succeeding stop lug 13.

When the shaft 8 is rotated counter clockwise, the lower crank 15 causes a corresponding movement of the lower spring end 19 while the upper end is held stationary by its engagement with the arm 40 until the detent 24 is retracted out of engagement with the instant stop lug 13 whereupon the movable pole member is thrown by a snap action in that direction.

In the construction shown in the drawing, the pole member is adapted to be moved into four functioning positions and accordingly the stop plate 9 is provided with four

stop lugs 13, but any other number of operating positions of the pole member would be cared for by providing the stop plate with the corresponding number of equally spaced lugs 13. By proportioning the operative end of the detent 24 substantially to fill the space between any two stop lugs 13, the movable member of the switch is definitely positioned in whichever direction the switch is operated and back lash is avoided.

While I have shown and described the best embodiment of the invention known to me, I desire not to be restricted thereto.

What I claim as new and desire to secure by Letters Patent of the United States is:

1. In a double action snap switch, the combination of an insulating base, a plate provided with spaced stops anchored to said base, an operating shaft journaled centrally of said spaced stops and provided with two crank projections, a movable pole member journaled upon said shaft, a spring surrounding said shaft within said pole member and engaging at both ends with said crank projections and with said movable pole member, a detent slidably engaging said pole member and having its operative end of a width to enter the space between any two of said stops with limited clearance, and an eccentric fixed to said shaft and engaging an aperture in the inner end of said detent.

2. In a double action snap switch, the combination of a base, spaced stops fixed to said base, an operating shaft journaled centrally of said stops, two crank projections fixed to said shaft at spaced points longitudinally thereof, a helical spring surrounding said shaft between said crank projections and having its ends bent outwardly normally to engage the respective crank projections, a movable pole member centrally apertured to receive the said spring therein, means projecting from opposite sides of said pole member for journaling it upon said shaft above and below said crank projections and provided with shoulders for normally engaging the bent ends of said spring outside said pole member, and detent means adapted to engage and disengage said spaced stops.

In witness whereof, I have hereunto set my hand this fourth day of February 1924.

GEO. W. LIEBERUM.
